UNITED STATES PATENT OFFICE.

EDWIN J. PRINDLE, OF EAST ORANGE, NEW JERSEY, ASSIGNOR, BY MESNE ASSIGNMENTS, TO UNITED SHOE MACHINERY COMPANY, A CORPORATION OF NEW JERSEY.

LAST-HEEL.

1,146,022.

Specification of Letters Patent. Patented July 13, 1915.

Application filed May 15, 1909. Serial No. 496,283.

To all whom it may concern:

Be it known that I, EDWIN J. PRINDLE, of East Orange, in the county of Essex, and in the State of New Jersey, have invented a certain new and useful Improvement in Last-Heels, and do hereby declare that the following is a full, clear, and exact description thereof.

The object of my invention has been to 10 provide a reinforcement for wooden heeled lasts which shall enable them to withstand having the heel driven on by a heeling machine; and to such ends my invention consists in the last heel hereinafter specified.

15 In the accompanying drawing illustrating one embodiment of my invention, Figure 1 is a side elevation, partly in section, of a last embodying my invention. Fig. 2 is a section on the line 2/2 in the direction 20 of the arrows, and Fig. 3 is a plan view of the heel portion of Fig. 1.

In the manufacture of shoes it is customary to drive the heel on the shoe at a single blow, driving all the nails which are 25 to connect the lifts of the heel together, and to the sole at one time. This puts an enormous pressure upon the last heel, and no last heel in which the strain is borne by the wood, as far as I know, previous to my last 30 heel has been so constructed that it could stand the pressure repeatedly without giving way. I have conceived that if a metal or other strong support be formed in the cone of the heel with a bearing surface on the 35 wood of the heel of sufficient area so that the wood is not crushed, and especially if the construction be such that the thimble hole shall be perpendicular to the heel plate of the last and at the center of the same, the 40 last will not crush. I have chosen to illustrate my invention, the embodiment thereof which is shown in the drawings, but it is to be understood that it is only one of numerous embodiments of which the principle of 45 my invention is capable. In such embodiment the last A has the usual heel plate B. An upper surface a is formed on the heel of the last, preferably about two-thirds or three-fifths of the distance from the heel 50 plate to the top of the cone, which surface is sufficiently large so that when properly supported it will not be crushed by the compression of the heeling machine. Experience has shown that the surface a should

preferably be at least half the area of the 55 heel plate B. Upon the said surface is a bearing part C, preferably of sheet steel. A thimble piece D is provided, which preferably has a cylindrical portion d fitting into a hole a' in the heel of the last, and 60 preferably having front and rear enlargements d' and d'' which bear upon the support of plate C. The contour of the last is filled out preferably by lifts of leather E which fit over the thimble piece and fit 65 down upon the said plate. Bolts F preferably pass through the said lifts and through the heel and are engaged by nuts f seated in recesses formed in the heel beneath the heel plate. I preferably put a fiber cap G 70 over the plate C so as to cover its edges and prevent any rust thereof reaching the lining of the shoe.

It will be observed that the strain upon the heel plate B is transmitted to the wood 75 and by the wood is transmitted to the plate C, and if the said plate is placed low enough in the last so that its area is sufficiently large, it will be able to support the wood without crushing into it. It will also be 80 observed that while the thimble piece sufficiently supports the plate, it is small enough so that it does not seriously add to the weight of the last.

As before stated, my invention is capable 85 of other embodiments than the one illustrated, and I desire not to be limited beyond the terms of my claims and the necessary requirements of the prior art.

I claim:

1. A heel for lasts comprising a wooden heel part, a heel plate on the tread face of said heel part, said heel part having a surface on the side thereof opposite to said plate of an area greater than half the area 95 of said heel plate, a plate bearing upon said surface, a thimble piece bearing upon the latter plate, and a filler disposed about said thimble to fill out the foot-shaped contour of the heel.

2. A heel for lasts comprising a wooden heel part, a heel plate on the tread face of said heel part, said heel part having a surface on the side thereof opposite to said heel plate of an area greater than half the area 105 of said heel plate, a plate bearing on said surface, and a thimble piece having forwardly and rearwardly projecting exten-

sions adapted to support the latter plate, said thimble piece projecting through the last mentioned plate into said heel part.

3. A heel for lasts comprising a wooden heel part, a heel plate on the tread face of said heel part, said heel part having a surface on the side thereof opposite to said heel plate of an area greater than half the area of said heel plate, a plate bearing on said surface, a thimble piece having forwardly and rearwardly projecting extensions adapted to support the latter plate, said thimble piece projecting through the last mentioned plate into the heel part, and a filling of light material surrounding said thimble piece and completing the contour of the heel.

4. A last having a heel comprising a wooden heel part, a heel plate on the tread face of said part, said heel part having a surface on the side thereof opposite to said heel plate of an area greater than half the area of said heel plate, a plate bearing on said surface, a thimble piece having forwardly and rearwardly projecting extensions supporting the latter plate, said thimble piece projecting through the last mentioned plate into the heel part, a filling of light material surrounding said thimble piece and completing the contour of the heel, and bolts passing through said filling and said heel part and bearing on the sole side of the heel part.

5. A last having a wooden heel part, said heel part being cut away below the cone of the last to form a bearing surface of large area, a metal thimble piece having an ex-

tended bearing on said surface and diminishing in cross section toward its top, and a filler disposed about the thimble piece to fill out the foot shaped contour of the heel. 40

6. A last having a wooden heel part, said heel part being cut away below the cone of the last to form a large bearing surface, a metal member bearing on said surface and extending nearly to the sides of the foot 45 shaped contour of the heel part, a covering for the edges of said metal member, a thimble supported by said member, and a filler disposed about the thimble to fill out the foot shaped contour of the heel. 50

7. A last having a wooden heel part, a reinforcing plate set into said heel part below the top of the last and extending nearly to the sides of the foot-shaped contour of the heel part, and a non-metallic covering separate from said wooden part for the edges of said plate. 55

8. A heel for lasts comprising a wooden heel having a metal heel-plate substantially covering the entire heel and having a surface located sufficiently below the cone of the last to provide an area larger than one-half that of the heel-plate to prevent crushing into the wood by the hereinafter mentioned thimble piece, and a metal thimble 60 piece adapted to support said surface. 65

In testimony that I claim the foregoing I have hereunto set my hand.

EDWIN J. PRINDLE.
